UNITED STATES PATENT OFFICE.

CARL E. BAUER, OF HAMMOND, INDIANA.

METHOD OF PRODUCING FULCRUMS.

Application filed February 7, 1921. Serial No. 442,921.

To all whom it may concern:

Be it known that I, CARL E. BAUER, a citizen of the United States, and resident of Hammond, in the county of Lake and State 5 of Indiana, have invented certain new and useful Improvements in a Method of Producing Fulcrums, of which the following is a specification.

My invention relates to a method of making 10 reversible fulcrums and particularly to a novel forged fulcrum which may be cheaply produced.

One of the objects of my invention is to provide a reversible fulcrum which may be 15 economically produced by a forging operation. Reversible fulcrums are required by many railroads in order to accommodate a single fulcrum to right and left hand beams and such fulcrums have heretofore been 20 formed by casting rather than by a forging operation. The device may be more cheaply produced by forging than by a casting operation and the fulcrum here described lends itself to manufacture in a simple manner.

It consists fundamentally of a single rectangular bar of uniform cross section and the required length the ends of which are first 25 bent at right angles and in the same direction from the bar. The bar is next flattened at an 30 intermediate point and then doubled on the flattened portion in such manner that the bent ends lie in overlapped relation. The bent ends are then suitably heated and forged to weld together the overlapped portions and 35 to square and distribute the metal in order to permit the fulcrum to be received in either of two positions between the flanges of a 40 brake beam channel. The opposite end of the fulcrum is then forged to provide a suitable strong seat for the tension rod.

The novel fulcrum and the method of producing it will be better understood by reference to the accompanying drawings in which,

Figs. 1 and 2 are plan and edge views respectively of the blank or bar which is utilized in making the fulcrum of my invention;

Figs. 3 and 4 are similar views showing 50 the next steps in the operation, that of flattening the center and bending the ends of the bar;

Fig. 5 is an edge view of the bar after it has been doubled on itself;

Fig. 6 is a view showing the fulcrum after 55 completion and in its operative position;

Fig. 7 is a view taken at right angles to that of Fig. 6;

Fig. 8 is a sectional view on the line 8—8 of Fig. 7, and,

Fig. 9 is an end view of the fulcrum after completion.

In the drawings it will be seen that the blank 10, which I employ, consists of an ordinary rectangular bar of iron or soft steel. 65 By a forging operation the middle portion 11, of the bar is flattened and the ends 12, 13, are bent at right angles, the portion 12 being somewhat longer than the portion 13. In the next operation the bar is doubled on 70 itself, on a line substantially midway between the ends, the line of bend being selected in order that the portions 12, 13, may lie in over-lapped relation, as shown in Fig. 5. Thereafter the bent end portion is suitably 75 heated and the metal caused to flow and be welded together by a forging operation. This results in the formation of a head 14, the shape of which is best shown in Fig. 9, and the provision of ribs or reinforcements 15, 80 on the side bars 16, 17. The head is not rectangular in outline as the fulcrum, in order to be reversible, must be turned 80°, for reasons well known to those familiar with 85 the subject.

After the head has been formed the opposite end is suitably heated and forged to produce the saddle 18, for the reception of the truss rod 19. The method of forming the saddle is described and claimed in my co-pending application, Serial No. 410,722, filed 90 Sept. 16, 1920.

The transverse openings 20 are provided for the brake rod pin and a longitudinal opening 21 for a fastening pin 22, which 95 passes through the web of the brake beam channel 23. The latter pin may be held in place by means of a key 24, best shown in Fig. 7.

A fulcrum constructed as described will 100 be found to be very strong and may be cheaply manufactured. Obviously the exact steps herein described need not be followed in detail or in the order named and I do not 105 wish to be limited except as indicated in the appended claims.

I claim:

1. The method of making reversible fulcrums which consists in providing a flat blank, bending the ends thereof at right 110 angles, then doubling the blank on itself in such manner that said bent ends are in

overlapped relation, then forging said overlapped ends and welding said ends together to produce a fulcrum having an angular end adapted to be received in two positions 5 between the flanges of a channel.

2. The method of forging fulcrums which consists in providing a blank, flattening the middle portion of the blank, bending the ends of the blank at right angles, then 10 doubling the blank on itself on the flattened portion, the bent ends lying in overlapped relation, then forging said bent ends to provide a squared portion adapted to fit in two positions between the flanges of a channel.

3. The method of forging fulcrums which consists in providing a blank, flattening the middle portion of the blank, bending the ends of the blank at right angles, then 15 doubling the blank on itself on the flattened portion, the bent ends lying in overlapped relation, then forging said bent ends to provide a squared portion adapted to fit in two 20 positions between the flanges of a channel, and then forging said flattened portion to 25 provide a tension rod seat.

4. The method of forming a reversible fulcrum which consists in bending the ends of a bar into substantial parallelism, the bent portions projecting in the same direction from said bar, then doubling the bar 30 on itself at a point sufficiently removed from the middle of the bar to cause said bent ends to overlap, then forging the end of said doubled bar to weld the bent portions together and to square the end. 35

5. The method of forming a reversible fulcrum which consists in bending the ends of a bar into substantial parallelism, the bent portions projecting in the same direction from said bar, then doubling the bar 40 on itself at a point sufficiently removed from the middle of the bar to cause said bent ends to overlap, then forging the end of said doubled bar to weld the bent portions together and to square the end, then forging 45 a tension rod seat in the opposite end of said fulcrum.

Signed at Chicago, Illinois, this 29th day of January, A. D., 1921.

CARL E. BAUER.
